UNITED STATES PATENT OFFICE.

ALFRED L. ROBBINS, OF OAKPARK, ILLINOIS.

BRACKET FOR UNIVERSAL STANDS OR SUPPORTS.

SPECIFICATION forming part of Letters Patent No. 757,498, dated April 19, 1904.

Application filed October 10, 1903. Serial No. 176,515. (No model.)

To all whom it may concern:

Be it known that I, ALFRED L. ROBBINS, a citizen of the United States, residing at Oakpark, in the county of Cook and State of Illinois, have invented certain new and useful Improvements in Brackets for Universal Stands or Supports, of which the following is a specification.

The object of this invention is the production of an improved adjustable bracket adapted to support articles of various sorts. While I have herein illustrated this device as being employed to support science apparatus, it is obvious that it is not limited to such application and that it may be used in many other connections.

In the accompanying drawings, Figure 1 is a side elevation, partly in section, of an apparatus-stand comprising two brackets embodying the features of this invention, said brackets being shown as supporting a combined color and siren disk and a motor for rotating said disk. Fig. 2 is a horizontal section on dotted line 2 2 of Fig. 1. Fig. 3 is a vertical sectional view through one of the brackets mounted on the main column of the stand. Fig. 4 is a horizontal sectional view through one of said brackets. Fig. 5 is a detail sectional view of the color-disk shank and the shaft for rotating the color-disk.

The universal stand illustrated in the drawings comprises a base 1, having three adjustable supporting-screws 2 of common construction, by means of which said base may be made level. Two only of these leveling-screws are shown in the drawings. The base 1 is provided with a central screw-threaded opening 3, into which the correspondingly-screw-threaded shank 4 of the main column 5 is intended to lie.

Two T-shaped brackets 6, identical in construction, are intended to be supported upon the main column 5, said brackets having a tubular body portion 7 bifurcated in its rear side and provided with two ears 8 and 9, through which ears the coinciding openings 10 and 11, respectively, extend. The opening 10 is internally screw-threaded to adapt it to receive the correspondingly-screw-threaded stem of the wing-screw 12, the opening 11 be-

ing of a diameter slightly larger to permit the passage of said stem. An annular shoulder 13, formed integral with said wing-screw 12, is adapted to bear against the outer side of the ear 9 to draw said ears together. The forwardly-extending portion 14 of each of the brackets 6 is of socket form, having the axial opening 15, and is provided upon its side with a boss 16, having an internally-screw-threaded opening 17 to receive the wing-screw 18. The opening 17 communicates with the axial opening 15 of the socket portion 14 of the bracket by means of the opening 19, which opening and the inner end of said screw-threaded opening 17 is adapted to receive a plug 20, preferably made of some soft metal, so that the pressure of the wing-screw 18 will not mar the shank of any piece of apparatus inserted into the opening 15. The opening within the tubular body portion 7 of each bracket 6 is counterbored, as at 21, and this counterbore is provided with a thickness of felt, paper, or other material suitable to offer a soft contact with the column 4. Both of the brackets 6 are adapted to be vertically adjustable upon the column 4 and to be secured to said column by a tightening of the clamping wing-screw 12.

22 refers to an electric motor having a shaft 23, with a grooved pulley 24 fixed upon said shaft. The motor 22 is provided with a shank 25, adapted to enter the opening 15 in the tubular portion 14 of the upper one of the two brackets 6 and by means of a belt 26 to furnish power to operate any piece of apparatus suspended within the lower one of said brackets—for example, a combined color and siren disk, which will be next described.

27 represents such combined color and siren disk, the inner portion 28 of the face of this disk being made up of the primary colors placed upon the disk in such relation that white is produced by a rapid rotation of said disk. Near the periphery of the disk 27 two concentric series of holes 29 and 30 for the siren demonstration are provided, the former being regularly spaced, the latter irregularly, in order to produce a musical note or discord, accordingly as the one or the other series is employed. The disk 27 is mounted upon a

shaft 31, rotatably supported in suitable bearings in the outer ends of the fork 32. Between the arms of this fork the shaft 31 carries a grooved pulley 33, fixed upon said shaft. 5 The forward end of the shaft 31 is provided with an opening 34 and a set-screw 35 for receiving and securing the shank 36, upon which the disk 27 is supported. A collar 37 is fixed upon said shaft, and the forward end of the 10 shank is screw-threaded to receive a thumb-nut 38. The rear end of the fork 32 is in the form of a stem 25, which stem is adapted to be inserted within the opening 15 of the forward socket portion 14 of the bracket 6. The 15 belt 26 is adapted to run from the pulley 24 to and over the pulley 33 to transmit rotatory motion from the motor 22 to the shaft 31. The brackets 6, or one only of them, may 20 be used for holding different articles of apparatus from that shown herein, it being only necessary that all apparatus intended to be used in connection therewith be provided with stems or shanks fitted to lie within the forwardly-extending socket portion 14 of said 25 brackets.

It is clear that many changes may be resorted to in the construction of this apparatus without departing from the spirit and scope of my invention, wherefore I desire to have it understood that I do not limit myself to the embodiment herein shown and described. 30

I claim as my invention—

An adjustably-movable bracket having a bifurcated tubular rear end with two perforated ears and a clamping-screw, also having a tubular forward end with an integral boss, which boss has a screw-threaded opening and an opening communicating between the screw-threaded opening in the boss and the tubular forward portion of the bracket, said communicating 40 opening being of a diameter less than that of the opening in the boss, a plug adapted to lie within the opening in the boss, said plug having a stem for extending through said intermediate opening, and a locking-screw for the 45 opening in said boss. 35
